Primary Examiner — Melody N Brown(74) *Attorney, Agent, or Firm* — Lionel D. Anderson; Reising Ethington P.C.(57) **CLAIM**

The ornamental design for a vehicle body exterior, as shown and described.

DESCRIPTION

FIG. 1 is a front elevation view of the vehicle body exterior; FIG. 2 is a front and left side perspective view thereof; FIG. 3 is a left side elevation view thereof; FIG. 4 is a top plan view thereof; FIG. 5 is a rear and left side perspective view thereof; and, FIG. 6 is a rear elevation view thereof. In the drawings, the portions shown by broken lines form no part of the claim, and the right side elevation view of the vehicle body exterior is omitted because the right side elevation view is identical to the left side elevation view except that the right side elevation view has a gas cap cover as shown by broken lines in the top plan view.
